VACUUM SLICE FOR PAPER MACHINES

Franklin J. Reilly, Chicago, Ill.

Application March 15, 1950, Serial No. 149,697

2 Claims. (Cl. 92—49)

1

This invention relates to paper making and more specifically, to an improvement in equipment for removing from the machine, water which is expressed from the paper web while it is being carried between a pair of felts. In some paper making machinery, a web of paper is deposited on a felt band and is pressed on the band by means of a second felt which is arranged to travel in the same direction and at the same speed as the felt on which the paper is deposited. These felts and the intervening web of paper contain a very large amount of water which is removed by passing the paper carrying felts over one or more supporting rollers which act to exert some pressure on the paper carrying webs to expel water therefrom, and between one or more pairs of press rolls, usually between several pairs thereof, which are arranged to successively exert increased pressure on the paper carrying felts for water expelling purposes.

It has been common practice to provide a baffle, a so-called slice, adjacent the nip of pressure rolls on the web receiving side thereof, and across the upper surface of the paper carrying felts. This slice acts as a dam to prevent the expressed water from flowing back over the surfaces of the felts and directs the water to flow toward the edges of the felts and off the same at its side edges. Suitable troughs are usually provided for collecting the water which runs off the felts at its sides. This arrangement causes a substantial pool of water to be collected between the slice and the nip of the adjacent press rolls.

According to the present invention, the conventional pool-forming slice above referred to is replaced by a vacuum slice which operates to remove the expressed water at a rate which is fast enough to prevent the formation of any substantial pool of water between the device and the nip of the press rolls with which the device is associated. By this means, the removal of water from the paper and felts is greatly facilitated so that each set of press rolls functions more efficiently with the result that the speed of paper formation may be substantially increased, that is to say, the paper making machine may be operated at a much higher speed.

The main objects of the present invention are, accordingly, the provision of means for accelerating the rate at which water may be removed from the paper carrying felts of a paper machine and from the paper carried thereby; and to provide water removing equipment of such effectiveness as to permit the paper machine to be operated at a much higher speed than has heretofore been

considered practicable, thereby increase the productive capacity of the machine.

It is also an object of the present invention to provide water removing equipment of the character indicated which will be of relatively simple and low cost construction and which can be easily and quickly applied to existing paper making equipment without significant alterations to the paper making machine or the press roll section thereof.

Other objects and advantages of the invention will be understood by reference to the following specifications and accompanying drawing in which there is illustrated a vacuum slice embodying a selected form of the invention and the manner in which the same is associated with a pair of press rolls of a paper making machine.

In the drawing,

Fig. 1 is a more or less schematic end view illustrating the manner in which the improved vacuum slice is associated with a pair of press rolls and the paper carrying felts which are acted upon by the press rolls;

Fig. 2 is a plan section approximately on the line 2—2 of Figs. 1 and 3;

Fig. 3 is a cross section on the line 3—3 of Fig. 2.

In the drawing, one pair of press rolls is represented by upper and lower rolls 1 and 2 respectively, these rolls acting on a pair of paper carrying felts which are directed between the rolls. An upper felt is indicated at 3 and a lower felt at 4, a paper web 5 being confined between these felts 3 and 4. The pressure rolls 1 and 2 are suitably mounted and driven so as to cooperate with each other to squeeze water out of the paper carrying felts and they are of ordinary construction and adjustable relative to one another to vary the pressure which they exert on the paper carrying felts. Some of the water squeezed out of the paper flows downwardly over the lower roll 2 and some of it is forced out of the upper surface of the upper felt 3 and tends to collect on the surface of the felt and against the surface of the roll 1. This follows from the fact that the felts are moving at a fairly fast speed toward the rolls 1 and 2 so that any water collected on the surface of the upper felt is carried toward the surface of the roll 1.

To remove the water which collects in this manner on the top of the felt 3, I provide a slice 6 which extends transversely over the entire width and preferably, somewhat beyond the edges of the felts. This slice is pivotally supported adjacent its front edge by a cross shaft 7 so that its rear 55 or intake edge 8 may be vertically adjusted rela-

3

tive to the surface of the upper felt 3. The cross shaft 7 is suitably supported on the framework of the paper machine by brackets or any other acceptable manner, and the intake edge 8 of the slice is supported to bear on the felt 3 under controlled pressure. To that end there is provided at each end of the slice, an adjusting device which comprises a screw-threaded rod 9 suitably anchored to the slice as indicated at 10 and extending downwardly and slidably through a suitably apertured ear or bracket element 11 which is rigid with the frame structure of the press section of the paper machine. A pair of nuts 12 on the threaded rod 9 above the supporting ear or lug 11 serves to sustain the intake edge 8 of the slice in the desired relationship to the surface of the upper felt 3. Spring means indicated at 13 about the rod 9 and under compression between the lower side of the ear or lug 11 and a wing nut 14 on the rod serves to yieldingly hold the intake 20 edge of the slice against upward displacement.

The supporting bolt 9 should be adjusted to cause the intake edge or toe of the slice to ride on the surface of the overlying felt with an ironing or smoothing action thereon, whereby smooth 25 paper web formation is attained and objectionable bunching and wrinkling of the felts avoided.

The slice 6 comprises a rigid frame structure having a pair of end members 15 and 16 which are rigidly interconnected by means of a longitudinally extending bar 17. This frame structure may be formed as an integral unit by casting or it may be fabricated from separate pieces as preferred.

A bottom plate 18 is suitably secured to the 30 frame members 15, 16 and 17 on the rearward or pressure roll side of the member 17 and a cover plate 19 is secured to said members 15, 16 and 17 in overlying relation to the bottom plate 18, thereby to cooperate with the latter and with 35 said members 15, 16 and 17 to form a chamber 20. This chamber 20 is closed except at the rear edge of the slice where an intake opening or slot is provided as indicated at 21. This intake opening or slot is provided between the rear edge 22 of the bottom plate 18 and a bead 23 which is formed at the rear edge of the cover plate 19. This bead may be bent up or down to adjust the width of 40 said slot or intake opening 21. The width of this opening does not appear to be critical and adjustment thereof by bending said bead as aforesaid is an adequate provision for that purpose. However, other forms of adjustment may be provided if desired. The said bead or lip 23 provides a 45 baffle which serves to prevent or at least reduce the flow of water over the nozzle and thence endwise along the nozzle and off the same beyond the edges of the felts.

The bottom plate 18 has its rear edge portion 50 bevelled or chamfered as indicated at 24 to provide a smooth non-cutting felt engaging surface.

For adapting the slice to various widths of felts, adjustable end walls 25 are provided adjacent the opposite ends of the slice between the bottom plate 18 and cover 19. These end walls 25 may each be made of a single plate element, but as here shown, they each comprise two parts indicated at 26 and 27, each part having a screw post 28 rotatably secured thereto. The screws 28 are threaded through suitably tapped openings which extend through the end members 15 or 16. By rotating the screws 28, the end wall sections or parts will be moved inwardly or outwardly according to the direction of turning of the screws 55 and the direction of the threading. By this

means, the effective length of the nozzle opening 21 and the chamber 20 may be substantially conformed to the width of the felts as shown. Meeting edges of the members 26 and 27 are preferably formed by bevelled faces indicated at 30.

Inside of the chamber 20, there is provided a 5 vacuum pipe 31 which extends along the entire length of the slice and projects through said end members 15 and 16. At one end, the vacuum pipe 10 31 is closed by a screw plug 32. The other end of the pipe is screw-threaded or provided with any other suitable fitting for facilitating connection of the pipe to an exhaust pump or other source of suction. Such connection is preferably made by means of flexible tubing such as high pressure hose which will resist collapsing under the effect of suction. The pipe may be removably or fixedly secured to the frame members 15 and 16, and in this instance it may be assumed to be fixedly welded or brazed to said frame members.

The suction pipe 31 is provided with a plurality of laterally extending branches 33, in this instance three such branches, disposed at suitably spaced intervals to approximately uniformly distribute the suction effect of the nozzle ends 34 of said branches over the effective length of the slice. In the construction illustrated, the slice is shown as tapering in its width from the main body portion thereof containing the suction pipe 31 to a reduced width or thickness at its intake edge. This facilitates positioning of the intake edge of the slice quite close to the nip of the press rolls. The branch suction conduits or pipes 33 have their intake ends somewhat flattened as indicated 35 at 34 to permit such end portions to closely approach the intake edge of the slice.

The suction pipe 31 with its branches 33 provides an effective means for removing and carrying away any water which collects on the surface 40 of the top felt. This suction pipe and branches, without the enclosing structure provided by the bottom and top plates 18 and 19 and the frame member 11, may be employed for the purpose of removing water but much greater efficiency is obtained by enclosing said suction pipe structure in the chamber 20.

It will be observed that the branch suction pipes 33 and their inlet ends are of relatively small cross section and that the combined areas 50 of the passageways in said suction pipes 33 is but a small fraction of the area of the intake opening or slot 21 of the nozzle of the slice. The branch suction pipes 33 are normally operated under a degree of vacuum or suction which produces a high velocity flow of water into the said suction pipes. The high velocity of water flow results in a water flow rate through said suction pipes which may be maintained substantially equal to the water flow rate through said nozzle opening 21 into the nozzle so that a balanced or substantially constant condition may be maintained in respect of the depth of water in the nip of the press roll and felt during normal operating conditions.

Although the flow rates of water into the suction pipes 33 taken as an entirety, and into the nozzle through the inlet opening 21 is approximately the same, it should be observed that the velocity of water flow in the pipes 33 will be much greater than the velocity of the water flow through the relatively large nozzle intake opening 21. The high velocity of the water flow in the suction pipes 33 tends to prevent plugging of said pipes by the lodging of water-carried solid material around the inlet openings of said pipes. The

relatively large size of the opening 21 in the nozzle, tends to avoid plugging of the nozzle inlet notwithstanding relatively lower velocity flow of water through such opening. Hence, the slice is, in effect, self-cleaning or non-plugging.

Another advantage of the described construction follows from the fact that it has been found to be much easier to make fine or close adjustments of water flow rates in the suction pipes 33 by controlling the vacuum applied thereto, than to similarly adjust the flow rates through a relatively larger intake opening such as the nozzle opening 21.

Hence, the arrangement described facilitates accurate adjustment of the water removing effect 15 of the slice to permit maintenance of a substantially constant water pool in the nip and in and around the mouth end portion of the nozzle of the slice.

Accordingly it has been found practicable to 20 maintain only a small pool of water in the nip but one which is nevertheless sufficient to maintain the suction pipe inlets immersed so as to prevent objectionable air sucking. The suction applied may be adjusted by suitable valve means (not shown) in the suction line leading to the slice. By adjustment of the suction, the amount of water permitted to collect in front of the press rolls and in the mouth edge portion of the slice may be effectively regulated.

The described vacuum slice may be employed in association with both the baby and main press rolls of a paper machine or at any point in a paper machine or like apparatus where water tends to accumulate on a surface. In an experimental installation of a vacuum slice embodying substantially the construction shown, on a cylinder paperboard mill, it was possible to increase the speed of paper production from about eighty-seven feet per minute to about one hundred fifty feet per minute without adversely affecting the characteristics of the paper web produced. The accelerated removal of water may be effected without changing the pressure of the press rolls on the paper web carrying felts, and good results may be attained even if the pressure is reduced somewhat. However, because of the decreased amount of water remaining in the sheet of paper and in the supporting felts, the press roll pressure may actually be increased without causing crushing of the rather fluid paper web. By improved removal of the water (called white water in the trade) the felts are kept cleaner and the life thereof is greatly extended. By the improved removal of water, the drier section of the paper machine is relieved of a considerable portion of its normal work so that substantial economies are possible in the operation of the drier section.

To facilitate adjustment of the slice toward and from the nip of the press rolls, the side members 15 and 16 may be slotted as shown at 35 to slidably fit on the hanger rod 7. Side plates 36 and 37 are provided with bearing bosses 38 which fit on the rod 7. These plates 36 and 37 are adjustably attached to said frame sides 15 and 16 by means such as pairs of bolts 39 which pass through slots 40 in the plates and are threaded into the frame sides 15 and 16. The pressure controlling bolts 9 are attached at 10, as aforesaid, to a lug which is attached to the side plates 36 and 37. The slice structure is thus adjustable between its side plates 36 and 37, the bolts 39 serving when tightened to lock the structure in selected position of adjustment. Certain of 75

said slots 40 are extended to also permit the passage of the adjusting screws 28 through the side plates without interfering with the described adjustability of the slice structure on its side plates 5 36 and 37.

The suction pipe 31 and its branches 33 may be flushed out with water under pressure by removing the plug 32, delivering water with a hose or the like into the open end of the suction pipe. 10 Some of the water so delivered into the suction pipe will serve to flush out the main pipe 31 and some will be diverted through the branch pipes 33 to clean the same. Other openings may be provided, if desired, to afford access to the chamber 29 for cleaning purposes, or the cover plate 19 may be removably secured in place so that said cover plate may in its entirety be removed if desired.

The various parts of the structure are preferably made of non-corrosive material. Although the structure is normally to be considered a rigid structure, it will be understood that because of its elongated form it will embody a certain amount of flexibility which will permit 25 a desirable degree of flexing or twisting of the device whereby conformation of the intake edge thereof to the surface of the overlying felt is greatly facilitated even though the felt may be running in a plane which is not strictly flat and 30 which may possibly be inclined more or less from one side of the felt to the other. The indicated flexibility of the structure will permit its being conformed, as aforesaid, to the 35 surface of the felt even through the hanger rod 7 is mounted somewhat out of parallelism with the plane of the felt.

In some installations, means may be provided for counterbalancing the weight of the slice to facilitate adjustment thereof in extremely small increments and to support the slice in very light, readily yielding frictional engagement with the felt. The mounting and supporting arrangement may, of course, be varied 45 to suit each installation, and various changes in the structure may be made without departing from the principles of the invention.

I claim:

1. A vacuum slice for withdrawing water from the nip formed between the upper roll of a pair of press rolls and the upper felt of a pair of felts which carry a wet paper web between such press rolls to enable the latter to squeeze water out of the web and felts, said slice comprising a nozzle adapted to be positioned so as to project into such a nip and having an elongated slot-like intake opening, the nozzle being of a width to extend across substantially the entire widths of such felts, a suction manifold associated with 50 said nozzle and adapted to be connected to a source of suction, a plurality of suction pipes connected to said manifold and having inlet ends disposed within said nozzle in spaced relation to each other across the width of said nozzle, said suction pipes having inlet ends adjacent said intake opening of the nozzle, said inlet ends being flattened to permit said inlet ends to closely approach said intake opening, the combined intake area of the inlet ends of all of 55 said suction pipes being substantially less than the area of said nozzle intake opening, said nozzle being provided with a substantially rigid, smooth-surfaced bottom part adapted to tightly engage the felt across the entire width thereof to substantially prevent water leakage be- 60 65 70 75

tween said nozzle and the felt, and means for maintaining said bottom part of the nozzle tightly engaged with the felt as aforesaid.

2. A vacuum slice for withdrawing water from the nip formed between the upper roll of a pair of press rolls and the upper felt of a pair of felts which carry a wet paper web between such press rolls to enable the latter to squeeze water out of the web and felts, said slice comprising a nozzle adapted to be positioned so as to project into such a nip and having an elongated slot-like intake opening, the nozzle being of a width to extend across substantially the entire width of such felts and having end walls adapted to be substantially aligned with the edges of said felts, and said nozzle having an upturned lip which serves as a baffle to prevent water from flowing over the top of the nozzle, a suction manifold associated with said nozzle and adapted to be connected to a source of suction, a plurality of suction pipes connected to said manifold and having inlet ends disposed within said nozzle in spaced relation to each other across the width of said nozzle, said suction pipes having inlet ends adjacent said intake opening of the nozzle, said inlet ends being flattened to permit said inlet ends to closely approach said intake opening, the combined intake area of the inlet ends of all of said suction pipes being substantially

5 less than the area of said nozzle intake opening, said nozzle being provided with a substantially rigid, smooth-surfaced bottom part adapted to tightly engage the felt across the entire width thereof to substantially prevent water leakage between said nozzle and the felt, and yieldable means for maintaining said bottom part of the nozzle tightly engaged with the felt as aforesaid.
